US00D923177S

(12) **United States Design Patent** (10) **Patent No.:** **US D923,177 S**
(45) **Date of Patent:** **** Jun. 22, 2021**

(54) **DRUG DELIVERY PUMP**

(71) Applicant: **UNL Holdings LLC**, New York, NY (US)

(72) Inventors: **Kun-Chi Wu**, Princeton, NJ (US); **Nicholas J. Ciccarelli**, Philadelphia, PA (US); **Conall Joseph Dempsey**, Philadelphia, PA (US); **John Burke**, Cambridge (GB)

(73) Assignee: **UNL Holdings LLC**, New York, NY (US)

(**) Term: **15 Years**

(21) Appl. No.: **29/638,015**

(22) Filed: **Feb. 23, 2018**

Related U.S. Application Data

(63) Continuation of application No. 29/508,588, filed on Nov. 7, 2014, now abandoned.

(51) **LOC (13) Cl.** **24-03**

(52) **U.S. Cl.**

USPC **D24/155**

(57) **CLAIM**

The ornamental design for a drug delivery pump, as shown and described.

DESCRIPTION

FIG. 1 is an isometric top perspective of a drug delivery pump;

FIG. 2 is another isometric perspective thereof;

FIG. 3 is a top view thereof;

FIG. 4 is a bottom view thereof;

FIG. 5 is a front view thereof;

FIG. 6 is back side view thereof;

FIG. 7 is a left side view thereof; and,

FIG. 8. is a right side view thereof.

The shade lines in the Figures show contour and not surface ornamentation.

Broken lines are for illustration purposes only and do not illustrate a part of the design sought to be patented.

1 Claim, 3 Drawing Sheets
